REVERSIBLE AND PROJECTED SASH
WINDOWEdmund Peremi, Manhasset, and Louis Toth,
Flushing, N. Y.

Application December 5, 1938, Serial No. 243,935

12 Claims. (Cl. 187—67)

This invention relates to window constructions and particularly to such constructions as have to do with reversible and projected sashes.

The chief object is to provide a construction whereby the window panes may be cleaned on both sides without taking a dangerous position outside of the window and without assuming difficult and straining positions on the room side of the window.

To this end, the preferred form of the invention incorporates one or more large window sashes which may be not only opened for ventilation but may be readily reversed in their window frames so that the outside surfaces of their window panes may easily be cleaned from the inside of the room. In the modified form of the invention the window is divided into a number of small independently or collectively movable sashes, which are similarly mounted as in the preferred form, but which need only be opened partially to reach their outside panes comfortably from the inside of the room for cleaning purposes. In our preferred form, due to the large window sashes, a complete reversal of the same is provided so that the outside of the panes may be reached.

Another object of our invention is to provide a means whereby the window sashes, large or small, will be frictionally held into whatever position they have been moved for either cleaning or ventilation purposes.

Another object of our invention is to produce window sashes having rails identical in shape which may be used interchangeably in complementary window frames.

Another object of our invention is to provide a locking means for the window sashes which is particularly adapted to the manner in which the windows open and close.

A still further object is to produce unit members which make up either the window sash or window frame which members are of durable, light, non-corrosive metal construction, simple in cross-section and readily extruded in one piece.

It is an object of this invention to provide a projected or swinging window having frictionally controlled means of improved construction for holding the window in any desired open position.

It is a further object of the invention to provide a swinging window in which the joint between the window and the frame is entirely sealed by at least three points of sealing contact when the window is closed.

It is a further object to provide such a window in which the supporting means for holding the window open may be completely concealed between the sash rails and the frame when the window is closed without interfering with the weather sealing contact.

It is a further object of this invention to provide a form of window in which a closed chamber surrounds the sash between the resilient sealing means and the outer zone sealing engagement of the sash and the frame whereby an air chamber is provided which surrounds the sash entirely, aiding in weather sealing and also acting as a gutter for water seepage.

Other objects and advantages will appear hereinafter.

Referring to the drawings:

Figure 1 is a fragmentary front elevation of a building wall which incorporates our invention and shows a double set of windows, part of one set broken away;

Figure 2 is a section taken on line 2—2 of Fig. 1 and shows the sashes of the window in open position and shows the reversed position of said sashes in dotted outline, and shows the curve described by the lower end of the sashes when they are moved to any position during their approximately 180° movement;

Figure 3 is a section taken on line 3—3 of Fig. 1 with intermediate sections broken away to permit enlargement and clarification of the details of the window frame and sashes;

Figure 4 is a section taken on line 4—4 of Fig. 1, looking in the direction of the arrows;

Figure 5 is a fragmentary section of our invention taken on line 5—5 of Fig. 1, showing enlarged details;

Figure 6 is a section taken on line 6—6 of the Fig. 1 and showing the lower sash of the window in elevation and in partially open position. The lower end of the upper sash is shown in section;

Figure 7 is a fragmentary front elevation of a building showing on reduced scale a modified form of our invention involving the window frames and the window sashes;

Figure 8 is a vertical section taken on line 8—8 of Fig. 7;

Figure 9 is a horizontal section taken substantially on line 9—9 of Fig. 7;

Figure 10 is a fragmentary detail of our invention taken on line 10—10 of Fig. 8;

Figure 11 is a section taken on line 11—11 of Fig. 7, showing the lowermost sash in open position;

Figure 12 is a front elevation of Fig. 11 with some portions in section;

Figure 13 is an enlarged detail section taken on line 13-13 of Fig. 12;

Figure 14 is a fragmentary sectional detail of the guiding and braking mechanism for the upper end of the window sash;

Figure 15 is a section taken on line 15-15 of Fig. 14;

Figure 16 is similar to Fig. 14, showing a modified form of the braking mechanism;

Figure 17 is a vertical fragmentary section taken of the meeting of the abutting portions of two adjacent window sashes to show a modified form of latching mechanism which holds the sashes closed;

Figure 18 is a fragmentary side elevation of Fig. 17, showing said latch mechanism;

Figure 19 is a perspective of the hand-operated portion of the latch;

Figure 20 is a perspective of the cooperating portion of the latch mechanism.

Referring to Fig. 1, numeral 1 indicates a fragmentary portion of the building wall enclosing a window opening 2 into which is incorporated the preferred form of window frame 3 movably mounting upper and lower window sashes 4 and 5 respectively. The window opening 2 encloses two window frames 3 but, as both windows have duplicate construction, only one of these windows will be described in detail. The window frame 3, Figs. 1, 3 and 4, is composed of side jamb members 6 and 7 connected by header and sill members 8 and 9 respectively. It will be noted from these figures that members 6, 7 and 9 are identical in cross-section and that header member 8 is modified in cross-section for reasons which will be apparent hereinafter. Window frame members 6, 7 and 9 are substantially I-beam in construction and may be extruded in one piece, having a back 10, inside and outside outwardly directed flanges 11 and 12 respectively, so as to form an outwardly facing channel, and inwardly extending flanges 13 and 14 to form an inwardly facing channel, flange 13 being longer than flange 14. The outwardly facing channel portions of the members 6, 7 and 9 are secured into the window opening 2 by metal angle bars 15. The header member 8 comprises substantially an outwardly facing channel having a back 16 with outwardly extending inside and outside flanges 17 and 18 respectively. An inwardly extending outside flange 19 is formed on back 16. The header 8 is secured to the building opening by an angle plate 20 having an angular offset 20a. The angles 15 and 20 which surround four sides of the window frame, and as stated, serve to secure the frame in the building wall, are preferably welded together at their corners whereby a strong and rigid supporting mounting frame is provided. Caulking material 21 serves to seal the entire window frame in position in the window opening.

Each inwardly facing channel portion of the frame members 6, 7 and 9 is so shaped as to house or imprison a V-shaped weather strip 22. Each back 10 of the above frame members carries an integrally formed rib 23 carrying a marginal lip 24, and an inwardly extending inside flange 13 which carries an outwardly extending striking lip 25. Also formed in each back is a shoulder 26 on flange 13 and a short supporting rib 27 formed between rib 23 and flange 13. The V-shaped weather strip 22 is of resilient non-corrosive sheet material, leg 28 bearing against

shoulder 26 and rib 27, and leg 29 bearing against striking lip 25 of the flange 13 under certain conditions, as will be mentioned hereinafter. The vertex 22' of the V-shaped weather strip is caught under the marginal lip 24 of the rib 23, and the inherent resiliency of the weather strip keeps it thus permanently imprisoned in its window frame member. The space 30 formed by the back 10, rib 23, and rib 27 permits the weather strip to be sprung into position when the window frame is assembled.

The header member 8 of the window frame is formed with a shoulder portion 31 which serves as a striking surface or flange for the movable window sash 4. Flange 19 of member 8 and flange 14 and lip 25 of frame member 9 serve as striking portions for the window sash 5 as will be described hereinafter.

The window sashes 4 and 5 are identical in vertical cross-section, as will be seen in Fig. 3 and are also identical in horizontal cross-section as shown in the Fig. 4. They are movably mounted, one above the other, in the window frame 3 and when in closed position fall substantially within the narrow dimensions of said frame.

Each window sash has identical rail members 32, 33 and 34. The members 32 and 34, comprising the vertical members, cooperate with the frame members 6 and 7, and the lower rail member 33 cooperates in the case of window sash 5 with the sill member 9, and in the case of the upper sash 4 with the upper rail member 35 of the lower window sash 5.

As the side and lower members or rails of both sashes are identical in cross-section, it will be sufficient to describe in detail the lower member 33 of the sash 5 which cooperates with the sill member 9 of the window frame 3. This rail member is hollow and rectangular in cross-section, having a peripheral wall 36, and inner wall 37, and inside wall 38 adapted to contact with striking lip 25 of the frame member 9, outside wall 39 having a striking flange 40 adapted to strike and contact with striking flange 14 of window frame member 9. The corner 41 formed by walls 36 and 38 of this sash member is adapted to engage and flex the leg 29 of the V-shaped weather strip 22 and thereby seal the window against air and water when said sash is closed. When the sash 5 is opened, the leg 29 of the weather strip will spring and engage the lip 25 of the flange 13.

The upper sash members 35 of the sashes 4 and 5 are identical in cross-section. They may be extruded in one piece and are hollow and rectangular in section as the other sash members 32, 33, and 34 and have corresponding walls 36, 37, 38 and 39. They have an outside upwardly directed striking flange 42, and the walls 36 and 38 carry a weather strip housing arrangement which is identical with the weather strip housing arrangement of the window frame members 6, 7, and 9 and therefore carry similar part members with the exponent *a* added thereto.

The weather strip housing of the rail 35 is in the same vertical plane as the weather strip housing of the window frame members, thereby creating a symmetrical arrangement. It will be observed also that the hollow rectangular portions of window sashes are also in perfect vertical alignment.

The meeting rails 33 and 35, Figs. 3 and 6, of the upper and lower window sashes bring about a meeting and sealing of the window by having outside flange 40 of the sash member 33 contact

outside and upwardly directed flange 42 of the sash rail 35, and by having wall 38 strike lip 25a and by having corner 41 flex weather strip leg 29a. The leader 8 of the window frame 3 and the sash rail 35 of the sash 4 seal and close the window in like manner.

The window sashes 4 and 5, Figs. 1 and 2, carry window panes 44 separated by horizontal and vertical muntins 45. The rail members of both sashes carry inwardly directed flanges 46 to be engaged by window panes 44 and carry inwardly turned undercut narrow outside flanges 47 which serve to aid in holding the putty 48 in position. Metal clips 47a may be provided which lock resiliently into position between flanges 46 and 47 and engage said panes.

The window sashes are so articulated to the window frame that the upper end of each sash partakes of a downward vertical movement and the lower end of the sash swings outwardly, upwardly and then inwardly on a curve 49 as shown in Fig. 2. This curve describes the complete reversal of a sash member so that the inner face of it is now turned outward. A preferred mechanism for producing this movement is as follows:

Mounted on the outside of window frame members 6 and 7 are channel track members 50 and 51. These channel members have their open sides facing each other and extend vertically the entire length of the window frame 3. The upper side ends of each window sash securely carry a pair of bearing blocks 52 (Figs. 1, 2, 4 and 6) which pivotally house stud shafts 53 of shoes 54 which are adapted to slide snugly up and down in the channel tracks 50 and 51. Each channel member has inwardly turned lips 55 in order more completely to house and guide its shoe 54 and to add rigidity to the channel. Each shoe is bifurcated, as shown in Fig. 14, to form leg portions 56 and 57 capable of being sprung slightly apart and adapted to bear against channel flanges 58 and 59 respectively. The space between the leg portions 56 and 57 houses a bowed spring 60 which is adapted to exert pressure tending to force the legs 56 and 57 apart and into frictional engagement with their respective channel track flanges 58 and 49. In this way a frictional drag is placed upon the window sash sufficient to hold it in any of its open or reverse positions. To adjust the friction produced by the pressure of the spring, a set screw 61 threaded into leg 57 of the shoe 54 bearing against the spring 60 is provided. To get at the screw 61, the guide channels have outside holes 62 which coincide with the closed position of the window sash and its brake shoe.

Each brake shoe is provided with a housing plate 63 having ends 64 and 65 bent at right angles to engage the top and bottom of the shoes. This plate 63 prevents the accumulation of dust and dirt in the bifurcated brake shoe and covers and retains the spring to be described. To produce friction, each bearing block 52 houses a compression spring 67 which is adapted to press against the end of stud shaft 53 so as to cause the brake shoe 54 to exert lateral pressure against the back 66 of its channel. The other end of the spring 67 bears against an adjustable screw 68 by means of which the lateral pressure of the spring 67 may be adjusted. Fig. 16 shows a modified form of brake shoe construction in which the bolt spring 60 has been omitted and in which the screw 70 tends directly to force apart the legs 71 and 72 of the brake shoe in order to produce the necessary retarding friction.

From the above it will therefore be understood that the upper end of each sash partakes of a vertical up and down movement and the friction drag of shoes 54 serves to counteract the force of gravity. To cause the lower end of each sash to describe the curve 49 shown in Fig. 2, a pair of stay bars 73 are provided. These stay bars, Figs. 2, 4, 5, and 6, are pivoted at their lower ends on pivot screw bolts 74 secured in the side window frame members 6 and 7 in line with the bottom of the connected sash and their upper ends pivotally secured by screws 75 to the sash side rails. These stays have a length slightly more than one-half the height of a window sash so as to produce the curve shown in Fig. 2.

Each stay bar, when its window sash is closed, is housed between the back 10 of the side window frame member, wall 36 of the vertical window sash member 32, flange 40 of the window sash member 32, and rib 23 of the backing 10 of the vertical window frame member (see Figs. 4 and 5). It will be observed that striking flanges 40 are long enough to span the spaces occupied by the stay bars and engage the flanges 12.

By means of this arrangement, the two stay bars of each window sash are not visible when the window is closed and thereby produce a very neat appearance from both the outside and inside of the window. It is further apparent that there is sufficient space between the flange 23 and the flange 14 to provide for concealment of the stays 73 without interfering with the sealing contact between the rail and the resilient tongue 22 of the weather sealing member, so that when the window is closed the weather sealing member provides for resilient contact on all sides of the window and the frame in addition to the contact made between the flanges of the frame and the sash rail respectively.

To prevent each stay-bars 73 from bearing against either the wall 36 of the window sash member or backing 10 of the window frame member when the window sash is moved, a thin washer 76 is interposed between stay rod 73 and the wall 36 at the pivot bolt 75, and a like washer may be interposed between the stay rod 73 and the backing 10 at the lower pivot bolt 74. Each bolt 75, Figs. 5 and 6, is countersunk at 78 in its bar 73, and is shouldered at 79 to bear against the wall 36 and is threaded into a block 80 which has been inserted into the rectangular frame member 32 of the window sash. The pivot bolt 74 is secured in the same way to the window frame member 10 and is threaded into one of the window frame supports 15 as shown in dotted lines in Fig. 5. In order to permit the movement of the stay bars 73 the inwardly directed outside flanges 14 of side members 6 and 7 are cut away at 14a, Figs. 4 and 6.

When the transverse friction pressure of the springs 67 is adjusted, both adjusting screws 68 should be turned through equal angular increments in order to keep the window sash side members properly spaced from the window frame members so that the stay rods will move freely between them without scraping.

With a window sash mounted as described the upper end of the same moves down and the lower end moves out to open the window and vice versa. When the upper end of the window moves down its track the full distance as determined by the length of its stay bars 73, the lower end of the sash describes the curve 49 shown in Fig. 2 bringing about a complete reversal of the window sash as shown in dotted lines, the partially

open ventilating position of window sashes 4 and 5 being shown in full lines. The frictional drag provided by the shoes 54 in guide tracks 50 and 51 will arrest the window sash into whatever position it may be moved.

When the lower window sash 5 has been fully reversed as shown in Fig. 2, it will be noted that its rail 33 overlaps the lower end of said upper window sash 4. Therefore, it will be necessary to move the lower sash out of the path of the upper sash so that the same may be moved to the desired position.

It will be noted from Figs. 2, 3 and 6 that due to the position of the sliding pivot point of each of the window sashes the upper contacting flanges and lips of each window sash strike their cooperating members from the inside of the room, and that the contacting flanges and surfaces of the lower members of each sash strike their cooperating members from outside the room, therefore, in order to lock collectively and individually the sashes 4 and 5 in closed position, a new and improved type of window latch particularly adaptable to the manner in which these window sashes move is provided. One latch serves to lock the meeting rails 33 and 35 of the window sashes and the other latch serves to lock the lower sash rail 33 of the window sash 5 to the sill member 9 of the window frame 3.

This latch, Figs. 3 and 10, comprises a fixed member 82 secured to the window sash 5 and a pivoted coacting member 83 secured to the sash 4. The fixed member comprises a body portion 84 secured to the flange 13a of the rail member 35, having an inwardly extending portion 85 terminating in a vertical upstanding locking finger 86. This finger is slightly resilient and has an enlarged tip 87. The finger extends above the upper edge of its window sash 5 and is adapted to be engaged by the movable locking member 83. This movable locking member comprises a horizontal locking body portion 88 which is bifurcated to form two arms 89 which embrace a bearing bracket 90 to which the arms are pivoted by means of a shaft 91. The locking portion 88 of the movable locking member 83 is adapted to be forced over the enlarged portion 87 of the locking finger 86 and to engage the face of said finger. The inner end of the locking member 83 terminates in an eye-ring 92 by means of which the locking member 83 may be raised or lowered into and out of locking position.

The cooperating locking parts 82 and 83 are so proportioned that only a slight flexing of finger 86 is necessary to permit the locking or unlocking of the latching parts. The raised position of latch member 83 is limited by a stop 93 carried on the arms 89 and adapted to engage the wall 38 of the meeting rail 33 of the sash 4.

As shown in Fig. 3, the latch above described is in locked position, thereby preventing either of said sashes 4 and 5 from opening, and the lower sash 5 is locked in closed position by a similar latch mechanism, wherein the fixed member 82 is secured to the flange 13 of the window frame member 9 and the movable member 83 carried by the sash member 33 of the lower sash 5.

Figs. 17 to 20, inclusive, show a modified form of the window sash locking mechanism in which a fixed member 82a is mounted upon the upper rail member 33a of a lower window sash in which a movable cooperating member 83a is pivotally carried on rail 35 of an upper sash. The fixed

unit comprises a wide and flat portion 84a having two integrally and diagonally upstanding spaced fingers 86a. These fingers 86a project above the upper edge of the sash and are adapted to be engaged by a pair of arms 88a which are connected by a hand-ball 92a and are pivotally carried in a bracket 90a secured to the upper sash. The bracket 90a has spaced ears 89a which pivotally support stud shafts 91a formed on the arms 88a of the pivotal locking member 83a. This pivoted locking member 83a carries locking cam portions 87a which are adapted to engage and lock over the fingers 86a of the fixed locking member 82a. The co-acting latching members are so proportioned that only a slight resiliency of the fingers 86a is necessary in order to provide the required locking pressure. In other respects this modified latching form acts in the same way as the preferred form and, in addition, the modified form provides a more convenient hand grip in the form of the hand-ball 92a.

Fig. 1 shows a window opening which incorporates two window frames 3 which are spaced apart by a mullion 94 which is shown in Fig. 4. The mullion 94 comprises a heavy sheet metal member bent into channel shape and includes legs 96 and offset parallel portions 97. The parallel portions 97 are secured to the adjacent window frame jamb members 7 and 6 and the legs 96 are snugly engaged by flanges 11 of these same window frame members so as to give a neat inside appearance to the adjacent window frame members and mullion 94. The outside flanges 12 of the window frame members 7 and 6 are connected by an extruded metal filler plate 98 which has grooves 99 engaged by the ends of the flanges 12. This filler plate 98 thereby gives a neat outside appearance to the mullion and is also weather proof.

In Fig. 6 is shown screwless glazing bead 44a which may preferably be applied to any form of the invention to guard the putty from deterioration, and also partially to support the pane 44. A glazing bead such as is shown in our United States Patent No. 2,119,685 may be used.

The modified form of window shown in Figs. 7, 8, 9, 11, 12, and 13 comprises a window frame 100 consisting of header 101, vertical jamb members 102 and 103 and sill member 104. Each window frame 100 is adapted movably to support a plurality of vertically arranged window sashes; four sashes 105, 106, 107 and 108 being shown for purposes of illustration. As the cross-section of all of the members which make up the frame 100 is identical, it will suffice to describe in detail the sill member 104.

This member, Fig. 8, is substantially I-shaped in construction, having a back 109 and inside and outside flanges 110 and 111 forming an outwardly facing channel, and inwardly directed flanges 112 and 113 forming an inwardly facing channel. The window frame 100 is secured in the window opening by angles 100a, which may be secured together at their corners to form, as in the preferred embodiment, a rigid mounting frame. The inside and inwardly directed flange 112 is somewhat longer than the outside flange 113 and has an outwardly turned striking lip 114. The inwardly facing channel of said sill member houses a V-shaped resilient non-corrosive weather strip 115, one leg 116, of which bears against a shoulder 117 formed on the flange 112 and against a narrow rib 118 formed on the back 109. The vertex 119 of said V-shaped weather strip

engages underneath a marginal lip 120 of said outside flange 113 and the other leg 121 of the sheet metal weather strip 115 extends diagonally so as to engage under the striking lip 114.

The space 122 permits the weather stripping to be sprung into position and imprisoned in the manner shown in Fig. 8. This weather strip is retained in position in the same manner as the weather strip shown in Figs. 3, 4, 5 and 6, of the preferred form but is much larger as it spans the entire channel opening of its window frame member.

As will be seen from Figs. 8, 9, 11, 12 and 13, all other members 101, 102 and 103 which make up the window frame 100 carry a weather strip 115 in the same manner as has been described.

Each window sash, 105 to 108 inclusive, comprises identical side rails 123 and 124 and bottom rail 125. Window sashes 106, 107 and 108 have unidentical top rails 126. The topmost sash 105 has an upper rail 125a which is identical in cross-section with the rails, 123, 124 and 125.

The identical rail members 123, 124, 125 and 125a are hollow and rectangular in section and have peripheral walls 127, inside walls 128, outside walls 129, and inner walls 130 (Figs. 8, 9, 11 and 12). Each peripheral wall 127 carries an outside outwardly directed flange 131 and outwardly directed inside flange 132. The side rails 123 and 124 of all the sashes 105, 106, 107 and 108 and lowest sash rail 125 and highest sash rail 125a engage their cooperating window frame members 101, 102, 103, and 104 so that flanges 131 strike flanges 113, flanges 132 strike lips 114, and the same flanges engage and flex the legs 121 of the weather strips.

The upper sash rails 126 of sashes 106, 107 and 108 (Figs. 8 and 11), have similar rectangular bodies. Each peripheral wall 127a carries a weather strip and weather strip housing similar to that of the member 104 of the window frame and accordingly similar parts have similar references with exponent "a" added. Therefore, when the cooperating rail pairs 125 and 126 of the sashes 106, 107, 108 meet flanges 131 strike flanges 113a, flanges 132, strike lips 114a and the same flanges flex weather strip leg 121a (Fig. 8).

The inner walls 130 carry panes 130a by means of flanges 130b and 130c as is well known in the art.

The upper ends (Figs. 8, 9, 11 and 12) of each sash are supported in the same manner as the sashes 4 and 5 of the preferred form, that is by being pivoted to blocks 50 running in tracks 51 except that the tracks are shorter. Accordingly similar parts have similar reference numbers. However, in the modified form the guide tracks 50 and 51 are mounted in pairs on the window frame members (Fig. 7), adjacent the upper ends of each sash. Each pair of guide tracks or channels is secured to the window frame members 102 and 103 near the upper end of its associated window sash. The lowest end of each track securely carries a stop block 136 for limiting the downward movement of the upper part of the sash (Figs. 11 and 12). Each block 136 has a drain hole 137 to prevent the accumulation of dust and dirt in the bottom of its track.

The lower ends of the sashes 105 to 108 inclusive, move in the same manner as the sashes 4 and 5 of the preferred form and have similar mechanism for doing it. For example, sash 108 has a pair of stay bars 138, Fig. 9, which have

their upper ends pivotally connected by pivot bolts 139 to the side walls 127 of the side rails, and have their lower ends only one of which is shown in Figs. 12 and 13, pivotally connected to the backings 109 of the window frame side members by screw bolts 140. Each stay bar 138, Fig. 12, is positioned between a backing 109 of a window frame member and the peripheral wall 127 of a side sash rail. The upper pivotal bolt 139 is countersunk into the stay bar 138 and threaded into block 141 inserted into the sash rail member before it is assembled and the stay bar is prevented from contacting wall 127 by a thin spacing washer 142 around the bolt.

The lower pivot bolt 140 is also counter sunk into the stay bar and projects through a thick spacing washer 144, through a plate 142, through backing 109 and is threaded into angle 100a which fixes the window frame in the window opening. As in the preferred form, when the sash is closed, each stay bar 138 is completely housed by backing 109, wall 127, flanges 112 and 113. The flange 132 of each side sash member is broken away at 143 (Figs. 11 and 12) to permit the movement of its stay rod 138. The weather strips 115 in the side window frame members 102 and 103 are broken into sections to make room for the pivot bolts 140, the spacing washer 144 and the plate 142. These sashes are provided with the same latches as used in the preferred form.

The sashes 105, 106, 107 and 108 are not reversible therefore their guide tracks 50-51 and stay bars 138 are shorter. However, the guide tracks stops 136 are so positioned and the stay bars so proportioned to sash and window frame that a maximum downward and outward movement of a sash is possible as shown in Fig. 11. This angle is sufficient to open the sash for ventilation and to enable the outside of its pane to be cleaned easily from the inside of the room.

The window frames 100 are mounted in pairs as shown in Fig. 7 and therefore have similar mullions 94 and 98 as described in the preferred form of our invention.

In the preferred form of the invention it is desirable to house one weather strip in each of the window sashes. This necessitated that the header member of the window be dissimilar from its component members, because of the manner in which the sashes close. Only four different unit members are necessary to make up the window frame and sashes.

In the modified form it was found advantageous to make the window frame out of one design unit member housing a weather strip in each section thereof. This symmetrical structure caused the uppermost window sash to be made unidentical in part in comparison with its companion sashes. This form of invention requires only four different unit members to make up the window frame and sashes. It is further observable that in the modified form the weather strip 115 extends substantially the full width between the striking surfaces of each sash rail. Inasmuch as this form contemplates the use of smaller sections for the sash and frame members provision is made for disposal of the stay bar 138 and the weather strip in the same channel when the window is closed.

The small number of unidentical extruded members required to construct the sashes makes for interchangeability of sashes and for quantity production of unit members and assembled frames and sashes. This permits the market-

ability of metallic windows and for low cost housing.

All parts of both invention forms may be formed of non-ferrous extruded metallic units for weather resisting reasons. Aluminum alloys are desirable because they are light in weight and thus produce windows that are easily assembled, and transported and readily incorporated in buildings. The weather strip is also preferably formed of non-ferrous springy material.

While we have illustrated and described in detail certain preferred forms of our invention, it is to be understood that changes may be made therein and the invention embodied in other structures. We do not, therefore, desire to limit ourselves to the specific construction illustrated, but intend to cover our invention broadly in whatever form its principle may be utilized.

We claim:

1. In a window, a jamb, a swinging sash, and a movable stay connecting said jamb and sash, said jamb and sash including cooperating members formed to provide mutually engaging surfaces adapted to provide inner and outer sealing contacts when the sash is closed and to provide a closed space extending longitudinally of the jamb and sash members, said stay being movable into concealed position in said space when the sash is closed, and a weather stripping member of resilient sheet material extending lengthwise of said space, said stay being movable into and out of said space without interference with said weather stripping member, one of said cooperating sash and jamb members being provided with a plurality of overhanging portions adapted to engage and retain said resilient weather stripping member in fixed association therewith.

2. In a window, a jamb, a swinging sash, and a movable stay connecting said jamb and sash, said jamb and sash including cooperating members formed to provide mutually engaging surfaces adapted to provide inner and outer sealing contacts when the sash is closed and to provide a closed space extending longitudinally of the jamb and sash members, said stay being movable into concealed position in said space when the sash is closed, and a weather stripping member of resilient sheet material extending throughout the length of said space, said stay being movable into and out of said space without interference with said weather stripping member, one of said sash and jamb members being provided with a plurality of overhanging portions adapted to engage and retain said resilient weather stripping member in fixed association therewith, the other of said cooperating sash and jamb members being provided with a surface extending throughout the length of the member engaging said resilient weather stripping member in sealing contact throughout the length of said weather stripping member when the sash is closed.

3. In a window, an outswinging reversible sash and a jamb, adjacent members of said sash and jamb being formed to provide a pair of longitudinally extending channels when said window is closed, a resilient metallic weather strip in one of said channels, and a stay for holding the sash in open position, secured to said jamb near the point on said jamb engaged by a corner of said sash when the window is in closed position, said stay folding into the other of said channels when the window is closed.

4. In a window, a frame including a jamb and a sash including a rail movably connected to the frame, the jamb comprising a face having an

outside inwardly directed flange, an inside inwardly directed flange terminating in an outwardly directed striking lip, an inwardly directed rib projecting from said face between said flanges, a V-shaped resilient weather strip housed on said jamb member between said inside inwardly directed flange and said rib, the sash rail member comprising a wall spaced from said jamb face and having an outside outwardly directed flange adapted to engage said outside inwardly directed flange of said jamb member, an inside wall engaged by said striking lip of said jamb and a portion of said rail being adapted to engage said weather strip, and a stay bar positioned between said jamb face and said sash rail having one end movably connected to said jamb and the other end movably connected to said rail, and adapted to be confined between said jamb and said rail when said cooperating members meet to close the window.

5. In a window, a frame, a sash having rails movably connected to said frame and adapted to open and close the window opening, guide tracks mounted on the sides of said frame extending the full length thereof exterior of the plane of the window, shoes in said tracks pivotally secured to said sash rails adjacent one end thereof, stays pivotally connecting points adjacent to the other ends of said rails and sides of said frame so that when the track guided end of the sash is moved from one end of said frame to the other end, said sash is substantially completely reversed and when the window is in closed position said stays are concealed.

6. A window frame member comprising a web, an outside inwardly directed flange, an inside inwardly directed longer flange having an outwardly directed striking lip, a shoulder adjacent to the base of said longer flange, an inwardly directed rib formed on said web between said flanges having a marginal lip, and a short rib formed on said web between said lipped rib and said longer flange.

7. In a window construction, a structural member comprising an extruded shape including a base web having a narrow flange at one edge thereof, a wide flange at the other edge thereof, said wide flange terminating in an overhanging striking lip, and an intermediate flange of less width than said wide flange, said intermediate flange projecting from the same side of said web as the other two flanges at a point on said web intermediate said first two mentioned flanges, said intermediate flange terminating in an overhanging lap facing the overhanging striking lip of said wide flange so as to provide a pocket for retaining a weather strip.

8. In window construction, a frame member including a base web, a narrow striking flange at one edge thereof, a wider flange at the other edge thereof, said wider flange terminating in an overhanging striking lip, an intermediate flange of less width than said wider flange projecting from said web between said two first mentioned flanges, said intermediate flange terminating in an overhanging lip facing the overhanging striking lip of said wider flange, and a weather strip formed of resilient sheet material bent into V-shape mounted in the space between said intermediate flange and said wider flange with the apex of the V engaged beneath the lip on said intermediate flange and the edge of the outer leg of the V engaged beneath the overhanging striking lip on said wider flange.

9. In a window, a window frame, a pair of

abutting swinging window sashes mounted in said frame, said sashes including a pair of cooperating meeting rails, the lower rail having an outside upwardly directed striking flange, a longer upwardly directed inside flange having an outwardly directed striking lip, and an upwardly directed intermediate rib having a marginal lip, a V-shaped resilient weather strip carried by said lower rail having one leg supported by said rail and the vertex engaged under said marginal lip on said intermediate flange and the other leg extending diagonally to engage under said striking lip on said inside flange, and said other meeting rail comprising a wall having an outside downwardly directed flange adapted to engage said outside upwardly directed flange of said lower rail, and an inside striking wall adapted to engage said striking lip on said longer inside flange of said first named meeting rail and adapted to form a corner with said first mentioned wall for engaging and flexing said diagonal leg of said weather strip.

10. In a window having a frame and a swinging sash mounted therein, a pair of cooperating frame and sash members, one of said cooperating members comprising a web having an outside striking flange, an inside longer flange having an outwardly directed striking lip, a rib formed on said web between said flanges and having a marginal lip, a V-shaped resilient weather strip imprisoned in said cooperating member having one leg supported by said web, the vertex of the strip being engaged under the marginal lip on said intermediate flange, and the other leg of said strip extending diagonally to engage under said striking lip on said inside longer flange, and the other cooperating member comprising a wall having an outside striking flange adapted to engage the outside striking flange on said first cooperating member, and having an inside striking wall adapted to engage the striking lip on

said longer flange on said first cooperating member and to form a corner with said first mentioned wall adapted to engage and flex said diagonal leg of said V-shaped weather strip.

- 15 5. 11. In a window having upper and lower swinging sashes a locking device comprising a slightly flexible and resilient locking finger mounted on the lower sash and projecting above the upper sash, and a pivotally mounted cooperating latching member carried by the upper sash adapted to engage and to lock over its cooperating locking finger when its sash is closed, said locking finger bending slightly to permit engagement and disengagement of said latching member, said latching member being held in locked position by the resiliency of said finger.
- 10 12. In a window, a frame, a sash mounted to swing in said frame to open and close said window, said sash having rails, said rails having inside and outside striking portions and said frame having inside and outside rail engaging portions complementary therewith, means for completely reversing said sash including guide tracks mounted on the sides of said frame 20 25 extending substantially the full length thereof exterior of the plane of the window, shoes slidably mounted in said tracks pivotally secured to said sash rails adjacent one end thereof, stays for holding said window in open position, pivotal connections at one end of said stays between said stays and said sash rails located between the inside and outside striking portions of said rails and pivotal connections between the other ends of said stays and the frame located 30 35 between the inside and outside rail engaging portions of said frame, said stays closing into completely concealed positions between said sash rails and said frame members when the window is closed.
